SUPERHEAT AND REHEAT CONTROL

Filed Sept. 17, 1948

UNITED STATES PATENT OFFICE

2,663,287

SUPERHEAT AND REHEAT CONTROL

Wilbur H. Armacost, Scarsdale, N. Y., assignor
to Combustion Engineering, Inc., a corporation
of Delaware

Application September 17, 1948, Serial No. 49,699

4 Claims. (Cl. 122—479)

1

The present invention relates to steam generators and particularly to an improved method of regulating the temperature of superheated steam in a generator equipped with superheating means.

In many power plants it is customary to utilize high temperature superheated steam in the high pressure stages of a steam turbine for driving generators or the like and, for the purpose of maintaining the thermal efficiency of the heat cycle, the exhaust steam from the primary stages of the turbine is frequently passed through a so-called reheat, which is a form of superheater, for the purpose of raising the temperature of the exhaust steam before admitting it to the secondary stages of the turbine. Where the superheater and reheat are located in the same boiler which also generates the steam, it is difficult to maintain uniform steam temperatures at all loads for both the primary superheater that supplies the high pressure turbine and for the reheat that supplies the low pressure stages of the turbine. Although the temperature of gases passing from the furnace over the superheater and reheat may be regulated in accordance with variations in load the effect of the gases on the reheat and superheater is not necessarily proportional and uniform at the various loads because it is practically impossible to design two pieces of heat transfer apparatus so exactly that the desired results can be predicated and attained at varying loads.

An object of the present invention is to overcome these disadvantages by regulating the temperature of gases from the furnace in accordance with fluctuations in the outlet temperature of steam from the reheat and maintaining a desired primary stage steam temperature without further regulation of the temperature of gases flowing over the reheat and then the superheater. The invention will be best understood upon consideration of the following detailed description of the illustrative embodiment thereof shown in the accompanying drawing in which the single figure is a diagrammatic elevational view of a water tube boiler having a primary superheater and steam reheat and in which the steam temperatures are regulated in accordance with the invention.

The boiler illustrated in the drawings includes a furnace 10 having its walls lined with water cooled tubes 12 connecting with the steam and water drum 14. The bottom of the furnace has two opposed sides sloping toward a throat 15 and faced with water cooled tubes 13. The two

2

remaining side walls also are lined with water cooled tubes 12 extending downwardly to the throat 15. The bottom and side walls above the throat thus form a water cooled hopper into which ash particles, gravitating from the fuel burning within the furnace, fall and, while falling, cool to a state in which they will not adhere to the sides of the hopper. Vertically adjustable burners 16 are arranged somewhat above the hopper bottom, and, preferably at the corners so as to project their streams of fuel and air into the furnace in directions tangential to the surface of an imaginary cylinder located vertically in the furnace, preferably in its center. Each set of burners shown discharges three fuel streams into the furnace. The rate of fuel firing is varied with changes in load but is not altered when regulating steam temperature at a particular load. The arrangement described above for the control of the outlet temperature of gases from the furnace 10 is the subject of Patent No. 2,363,875 issued on November 28, 1944, to Henry Kreisinger and Virginius Z. Caracristi.

In operation when all of the burners are adjusted to project the fuel and air streams in a substantially horizontal direction tangent to an imaginary vertical cylinder located centrally of the furnace, the burning fuel streams issuing from the four sets of corner located burners impinge upon one another resulting in a turbulent, rotating mixture with a consequent rapid rate of combustion. This rapid combustion produces a very high temperature in a zone A at the level of the burners near the bottom of the furnace so that there is a high rate of heat transfer from the flames to the water cooled wall tubes 12 in this zone both by radiation and by convection. Leaving this zone the hot products of combustion pass upwardly and continue giving off heat to the water cooled walls thereabove and exit from the furnace at a relatively low temperature. Greater heat absorption from the gases and a lower gas exit temperature may be achieved by depressing the burners below the horizontal so that combustion takes place in the zone D. When all of the burners are directed upwardly the streams of fuel are still tangent to an imaginary vertical cylinder in the furnace but the impingement of the burning fuel streams upon one another is much less than when the burners are horizontally directed as above described. This results in but relatively little mixing and turbulence and consequent slower or delayed combustion. This delayed combustion occurs in a zone B, that is located higher in the furnace than the zone A, and extends well into

the upper part of the furnace. Consequently, the temperature of the products of combustion leaving the furnace is relatively high because of the shorter path through which they pass from the combustion zone to the outlet of the furnace and because the heat transfer from the flames to the water cooled walls at the bottom of the furnace is substantially less than with horizontally directed streams. The change in the direction of the fuel streams from the horizontal to an upward inclination results in a rise in the temperature of the gases leaving the furnace which has been found adequate to change the rate of heat absorption by the reheat 20 and the primary and secondary superheaters 21, 22 so that the steam temperature may be raised to that required for satisfactory operation over a greater range of ratings of the steam generating unit than heretofore attainable.

In addition to the primary superheater 21 and secondary superheater 22 the present invention utilizes a reheat 20. The high temperature steam from the primary superheater 21 is taken from its outlet header 23 and on its way to the inlet header 24 of the secondary superheater 22 passes through a spray type de-superheater 25 into which water is injected by regulation of a valve 26 subject to fluctuations in the temperature of superheated steam in the secondary superheater outlet 27 as indicated at 28. From the outlet 27 of the secondary superheater 22 the steam passes through a conduit 30 to the high pressure stages of the steam turbine, not shown. The exhaust steam from this stage of this turbine is returned through a conduit 32 to the inlet header 33 of the reheat 20 and after the steam is reheated, it is directed through a conduit 34 to the secondary stage of the turbine. The final temperature of steam from the reheat 20 is regulated by tilting the burners 16 upwardly as the temperature of the reheated steam falls or downwardly as this temperature becomes excessive. The regulation of the gas temperature at the outlet of the furnace 10 may be controlled automatically by providing motors 38 to tilt the burners 16 and subjecting the operation of these motors to the outlet temperature of steam from the reheat through a thermostat 39.

In order to obtain uniform heat from the reheat 20 over a wide range of capacity the fuel burners for the furnace 10 are tilted upwardly or downwardly in response to decreases or increases in the steam temperature so as to vary the temperature of gas from the furnace in passing over the reheat in such manner as to maintain a constant outlet reheat temperature. The temperature of steam for the high pressure stages of the turbine is maintained by providing slightly more surface in the primary superheater than is required and then controlling the temperature by passing the steam from the primary superheater 21 through the desuperheater 26 to which water is admitted on fluctuation of outlet temperature from the secondary superheater 22. The primary superheater 21 need be over-surfaced only slightly because the temperature of the gases that pass over it is being controlled for the reheat which at the same time effects a major control for the primary superheater. For example, at half rating about half of the maximum amount of fuel that may be burned in the furnace is delivered to the furnace near the bottom and burned there in zone A; the products of combustion likewise are

about half and dwell within the furnace and are exposed to the cooled walls about twice as long as at full rating. The exit temperature of the gases may then be too low for reheating the steam to the temperature desired. By raising the zone of combustion within the furnace and delaying combustion by decreasing turbulence, the dwell of the products of combustion within the furnace is reduced as is the area of cooled furnace walls exposed to the gases.

It is deemed preferable not to control the primary steam temperature by tilting the burners 16 and then to regulate the reheat temperature by a spray desuperheater because whatever water is used for controlling steam temperature should pass through the complete turbine cycle so as to avoid impairing the work done in the several stages of the turbine. If an excessive reheat temperature were to be decreased by a water spray, an additional amount of steam would be produced which would then pass through the low pressure stage of the turbine without having passed through the high pressure section with the result that there would be a degradation of heat from the thermo-dynamic standpoint.

What I claim is:

1. The method of regulating temperature of steam from a superheater and associated reheat handling the same steam and absorbing their heat mainly by convection from gases leaving an outlet at one end of the same vertical water cooled tube furnace comprising; introducing fuel and air from a plurality of points into a part of the furnace remote from the furnace outlet in such directions as to create a turbulent gas mass burning in a zone remote from the furnace outlet to transmit heat to the water tubes therein; maintaining, for a given load, a substantially uniform rate of fuel firing; desuperheating the superheated steam from the superheater in proportion to variations of its temperature from a predetermined value for maintaining the superheated steam temperature at said value; and altering in response to variations in reheat steam temperature from a determined value the angle to the horizontal of the direction of the streams of fuel and air so as to move the location of the combustion zone along the furnace axis further from or closer to the furnace outlet as the reheat steam temperature respectively increases or decreases to thereby alter the extent to which gases are cooled before reaching the reheat and the superheater.

2. The method of regulating temperature of steam from a superheater and associated reheat handling the same steam and absorbing their heat mainly by convection from gases leaving an outlet at one end of the same water cooled tube furnace comprising; introducing fuel and air from a plurality of points into a part of the furnace remote from the furnace outlet in such directions as to create a turbulent gas mass burning in a zone remote from the furnace outlet to transmit heat to the water tubes therein; maintaining, for a given load, a substantially uniform rate of fuel firing; injecting water into the superheated steam in proportion to variations of its temperature from a predetermined value for maintaining the superheated steam temperature at said value; and altering in response to variations in reheat steam temperature from a determined value the angle to the horizontal of the direction of the streams of fuel and air so as to move the location of the combustion zone along

the furnace axis closer or further away from its outlet as the reheated steam temperature respectively increases or decreases to thereby alter the extent to which gases are cooled before reaching the reheat and the superheater.

3. The method of regulating temperature of steam from a superheater and associated reheat handling the same steam and absorbing their heat mainly by convection from gases leaving an outlet at one end of the same vertical water cooled tube furnace comprising; introducing fuel and air into the furnace from a multiplicity of points remote from the furnace outlet and in directions substantially tangential to an imaginary vertical cylinder located centrally in the furnace for creating a turbulent rotating gas mass in a zone located in a portion of the furnace remote from its outlet to transmit heat to the water tubes therein; maintaining, for a given load, a substantially uniform rate of fuel firing; and, as the reheated steam temperature increases, decreasing the vertical angle of the directions of fuel introduction relatively to the furnace walls to thereby increase the extent to which gases are cooled before reaching the superheater and reheat; and injecting water into the superheated steam in proportion to fluctuations of its temperature from a predetermined value.

4. The method of regulating temperature of steam from a superheater and associated reheat handling the same steam and absorbing their heat mainly by convection from gases leaving the outlet of the same water tube cooled furnace comprising; introducing fuel and air into the furnace for creating a gas mass to radiate heat to the water tubes thereof; maintaining, for a given load, a substantially uniform rate of fuel firing; passing the gases from the furnace over the reheat and reheating steam passing therethrough, directing the gases subsequent to their

10 passage over the reheat into contact with superheating elements of a capacity capable of heating the steam to a temperature above a predetermined value desired at other loads than the maximum designed load; and as the reheated steam temperature increases, increasing the amount of cooling of the gases of combustion in imparting heat to said water tubes prior to discharge from the furnace so as to lower the temperature of gases flowing over the heater and reheat; and injecting water into the superheated steam in proportion to fluctuation of its temperature from said predetermined value to reduce said temperature to said value at loads other than the maximum designed load.
